GOLF BALL WASHER AND DRIER

John C. Stutz, Kansas City, Mo.

Application May 1, 1933, Serial No. 668,764

3 Claims. (Cl. 15—21)

This invention relates to golf ball cleaning and drying appliances for use in club houses or at selected points of a golf course or links, and my primary object is to produce an appliance characterized by subjecting each ball washed to an automatic drying treatment prior to its recovery by the player or his caddy. Heretofore, as far as I am aware, no device for washing or cleaning a muddy or dirt-discolored ball, has possessed an automatic drying accessory, that is, a means for effecting a wiping or moisture absorbing action or both, and thereby avoid the necessity of hand-wiping the ball with a towel or the like.

Another object is to provide a construction having a receptacle and means for successively delivering cleaned and wiped balls to said receptacle from which they may be removed in condition for instant use, by player or caddy.

A still further object is to produce a cleaning and drying device of unlimited capacity, which cannot clog, which shields the operative parts to avoid chance of injury to the hands or clothing, and in which provision is made for the ready removal of the tank for the quick discharge of muddy and replenishment of clean water or solutions.

Another object is to provide a magazine for holding a number of balls, and means for effecting successive delivery of the balls to the cleaning elements, in spaced relation.

With the objects named in view, and others of a tributary character, the invention consists in certain new and useful features of construction and combinations of parts as hereinafter described and claimed; and in order that it may be fully understood, reference is to be had to the accompanying drawings, in which:—

Figure 1 is a top plan view of a combined golf ball washer and drier.

Figure 2 is a side elevation of the appliance.

Figure 3 is a central vertical longitudinal section of the appliance.

Figure 4 is a rear end view of the appliance.

Figure 5 is a cross section on the line V—V of Figure 2.

Figure 6 is a front end view with the hand-wheel broken away.

Figure 7 is a section on the line VII—VII of Figure 6, with the ball magazine broken away.

Figure 8 is a fragmentary perspective view of the rear end of the frame and a bracket for the support of ball drying elements.

In the said drawings, 1 indicates a rigid rectangular frame and within the same is a cylindrical rotary brush 2, flanked at opposite sides

by a pair of similar side brushes 3 and 4, the brushes being in parallel relation and disposed to form a ball-washing channel of which brush 2 forms the bottom, and the shafts of the brushes are journaled at their opposite ends in the front and rear end walls of the frame. Vertically above and parallel with brush 2 and spaced therefrom to depend within the said channel, is a spiral conveyor 5 of substantially greater length than the frame. The conveyor extends through an opening 6 in the rear wall of the frame, and its shaft is journaled at its front end in the front wall of the frame and at its rear end, in a bearing bracket secured as shown (see Figure 8), or otherwise, to the frame. To avoid undesirable weight and yet have stability, the bracket comprises a base 7, an arm 8, and a pair of side arms 9, the base being shown as secured to the rear wall of the frame. The bracket, as shown, has other parts and functions hereinafter mentioned. The brush-formed channel for washing the balls provides a path for the travel of each ball, and the spiral conveyor depends within the channel far enough to overlap and engage a ball or balls in the channel.

To impel travel of the ball rearwardly within the channel, the conveyor is rotated, and to effect such action, its shaft is provided at its front end with a hand-wheel 10 exterior to the frame, part of the handle being preferably in the form of a disk equipped at its rear side with a cam 11 for a purpose hereinafter explained. It is desirable that the brushes shall rotate, as by so doing they will scrub the ball more efficiently and mud accumulated from the balls will be readily dislodged and fall into the cleaning liquid or solution tank 12, in the contents of which brush 2 is almost wholly and brushes 3 and 4 are partially immersed. The tank receives the lower part of the frame 1 and, as shown, has outstanding lugs 13 for detachable engagement by a pair of spring catches 14 or the like on the frame.

The tank encloses the frame to about the level of the bottom of the ball channel, so that no packing or the like, is necessary against leakage of the liquid through the bearing openings provided for the shaft of brush 2, and in this connection it will be noted that the opening 6 in the rear wall of the frame, has a reduced extension 15 in line with the ball channel, for the escape of the cleaned balls (see Figures 3 and 8). Any suitable power-transmission may be employed between the conveyor shaft and the brushes, that shown being a train of gear wheels 16, 17, 18 and 19, on the shafts of the conveyor

and rotary brushes 3, 4 and 2, respectively. The gear wheels 17, 18 and 19 are immersed more or less in the water or solution in the tank (Figure 3), and to avoid corrosive action all the shafts 5 and the gearing and the conveyor should be of non-corrosive metal.

A magazine for receiving a plurality of balls and feeding them successively to the conveyor at the front end thereof, is in the form of an upright tube 20, shown as supported by a cover 21 for the frame, and to prevent but one ball at a time dropping on the conveyor in each revolution thereof, a spring plate 22 is secured to and projects into the tube to normally constrict the 10 passage thereof, and said plate is caused to move outward once in each revolution by the cam 11 of the hand-wheel, tripping a small bell-crank lever 23 linked as at 24 to the free or lower end of the spring plate, the latter returning to its 15 normal position through its resiliency, immediately the cam clears the bell crank. To insure the retention of the ball within the washing channel and in contact with the three brushes until ejected by the conveyor through the extension 15 of opening 6 in the rear wall of the frame, the 20 brushes 3 and 4 are about in peripheral contact with the conveyor (see Figure 5). Each ball as fed by the conveyor into the channel must pass between the conveyor and brush 3, and to enable 25 it to pass, the latter has a peripheral pocket 25, so disposed that as each ball passes downward beyond the axis of the conveyor, it enters said pocket (see Figure 5), and remains therein until the pocket is about in the horizontal plane of 30 the axes of the brushes 3 and 4, and the ball is forced out and under the then overlying conveyor, and by centrifugal force, out of the pocket and into the washing channel where it is in contact with all of the brushes and its upper part 35 is far enough within the groove or channel of the conveyor to be caused to travel rearwardly while subjected to the scrubbing action of the rotating brushes, it being obvious that as all of the brushes are partly immersed in the liquid 40 of the tank, their turning action results in mud gathered from the balls, being dislodged into and dissolved by the liquid, and because of this many balls may be cleaned without frequent replenishing of the supply of liquid.

To provide for a drying treatment of the balls as they successively pass through the opening-extension 15, a stationary drier, such as a brush or the like of substantially U-shape in cross-section and open at its ends, provides in effect an 45 extension of the ball channel. As shown, the drier is composed of three brush elements, a bottom one 26 and two side ones 27. The bristles face inwardly, and the conveyor depends within the drying channel so as to force the balls to travel 50 rearwardly against the bristles for the removal of the moisture from the balls, and the travel should be long enough to insure a substantially complete drying treatment by the time the balls reach the rear end of the conveyor. To avoid the necessity 55 of a player or caddy being ready to catch each ball as it is ejected by the conveyor at the rear end of the drying element, a perforated tube 28 is disposed to receive the successively discharged balls and deliver them to a cage 29 from which 60 they are removed when desired. The cage is preferably supported from the leg structure 30 or other suitable support, of the frame, the leg structure shown being such that it does not interfere with the ready removal and replacement of the 65 tank. The drying element or brush is preferably 70 75

sectional in character for economical reasons, as one part may wear faster than another and require more frequent replacement, and to facilitate removal and replacement, the brush sections or elements, have longitudinal ribs 31 slidably fitting channel bars 32 flanking the side elements and underlying the bottom element. The side channels are shown as integrally formed with the bracket arms 8, and the bottom channel bar is made integral with the side bars by arcuate 10 connecting sections 33. Clamping screw 34 may be employed to hold the brush elements against accidental shifting or displacement, or the removable yoke 35 may serve the same purpose, the yoke being secured to and depending from the rear 15 part of the bracket and forming a support for the upper end of the tube 28, the opposite end of the tube being preferably supported within a collar 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300

As frequent rapidly-recurring operations may 20 wet the drying element slightly so that the balls leave it not thoroughly dry, it is desirable that the tube 28 shall be of foraminous type for utilizing air circulation as an aid in the drying operation, and the tube may also contain pieces of absorbent material 37, to take up moisture from the balls passing to the receptacle. It may also have flexible absorbent wiping pieces 31a to be pushed aside by and wipe the balls as they pass.

As the parts are shown, the water level cannot stand higher than the bottom of the extension of opening 6, giving about full immersion to brush 2, and but little immersion of brushes 3 and 4, it may be desirable to effect a greater area of immersion of brushes 3 and 4, by causing the frame and brushes to slope upwardly toward the rear. This can be most simply and cheaply accomplished by making the front part of the leg structure shorter (not shown) than the rear part, by blocking up the rear legs, or in any other 40 equivalent manner.

As a precaution against injury to hands or clothing, the train of gearing is within the frame, and a semi-cylindrical hood or shield 38 fits over the conveyor where the same overlies the drying element or brush, the hood being secured at one end to frame 1 (Figure 3), and having lugs 39 at the other end to rest on the bracket. To effect removal of the drying brush or either of its elements, if it is of sectional construction as shown, the yoke 35 is removed. If set screws 34 are employed either in association with the yoke or in the absence of the latter, such set screws will have to be partly unscrewed. When held by neither the ring nor set screws, the drying element as a whole, or sectionally, can be slid out of engagement with the bars 32.

Normally a ball dropped into the magazine is caught and held by the spring plate, the latter being stiff enough to support a column of a half dozen or more balls. The hand wheel is then turned in the direction indicated by the arrow, Figure 6, as a pawl and ratchet mechanism 40 inhibits reverse movement. As the pocket 25 of brush 3 attains a position under the magazine, the cam 11 passes and operates the bell-crank, and the plate 22 is sprung outward to permit the engaging ball to drop, and then freed to snap back and catch the next ball. The dropped ball enters the brush pocket so that as the brush 3 and conveyor continue their turning movement, the ball is brought to a position below the axis of the conveyor and in the horizontal plane of the washing channel. As it attains such position, it is projecting into the channel and either falls or is 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300

forced out of the pocket to lie wholly within the channel, it being caused to travel rearwardly because it continues to project into the groove of the rotating conveyor. Under this travel and the 5 scrubbing it gets from the wet rotating brushes forming its underlying and side supports, it is thoroughly cleansed by the time it reaches and is forced through opening extension 15 into the drying element or brush, along which it travels 10 under the force of the conveyor until the latter ejects it into the tube 28 and it passes to the receptacle 29.

As the first full revolution—starting with the brush pocket 25 in ball-receiving position at the 15 bottom of the magazine—is completed, a second tripping of the spring-plate is effected and another ball dropped from the magazine, this second ball and each succeeding one being spaced 20 one revolution of the conveyor behind the preceding ball. It will be apparent, therefore, that the magazine can be charged to capacity and the balls will pass through the washing and drying elements without conflict and without contact 25 one with another. It is essential that the conveyor and brush 3 shall turn cooperatively and at the same speed, so that the pocket shall receive and insure passage of the balls to the washing channel. The direction and speed of rotation of brushes 2 and 4 is unimportant as the 30 latter, even though it may tend to lift the ball in the channel, is too close to the conveyor for a ball to escape from the channel between said brush and the conveyor, and a differential speed will, in fact, increase the frictional contact with 35 the ball and hence scrub it more effectively than if all the brushes turned at the same speed.

From the above description it will be apparent that I have produced a device possessing all of the features of advantage set forth as desirable, 40 and while I have described the preferred embodiment thereof, it is to be understood that I reserve the right to all changes properly falling within the spirit and scope of the appended claims.

45 I claim:—

1. In a golf ball washer and cleaner, a bottom and two flanking cleaners of cylindrical form disposed in parallelism to form a ball-receiving channel, a rotary spiral conveyor above the bot-

tom cleaner and depending into said channel and in close relation to the flanking cleaners to inhibit lateral passage of a ball between either of the last-named cleaners and the conveyor from the channel, one of the flanking cleaners having a peripheral pocket to receive a ball at and while engaged by the front end of the groove of the conveyor, and cooperate with the latter in carrying the ball to and ejecting it from the pocket into the channel without disengaging it from the 10 groove of the conveyor.

2. A device of the character described, comprising a frame having inlet and exit ball-passage openings, a tank detachably secured to and underlying the frame, a bracket projecting from 15 the exit-opening end of the frame around said exit opening and provided with a ball discharge opening alined with said exit opening, a rotary spiral conveyor journaled in and extending through the frame and bracket with its axis in 20 a plane parallel with and above the axis of said openings, a rotary brush within the frame and underlying and spaced from the conveyor, a pair of rotary brushes flanking and in a plane between 25 those of the first-named brush and conveyor and in close proximity peripherally with said first-named brush and conveyor, the top of the tank lying in a plane above that of the bottom of the flanking brushes, and means underlying the conveyor exteriorly of the frame and forming a drier 30 for golf balls and a guide to direct the balls to said discharge opening of the bracket.

3. In a device of the character described, a frame adapted for receiving a golf ball and provided with a ball-discharge opening in one end 35 wall, a rotatable spiral ball-conveyor extending through said discharge opening, a series of rotary brushes geared to and paralleling the conveyor and depending to a plane below that of said opening and providing a channel to hold balls in 40 engagement with the conveyor and in alinement with said opening for passage therethrough, shafts for said brushes, journaled in the front and rear walls of the frame in a plane below that of said opening, and a tank externally embracing 45 and detachably secured to the casing, the top of the tank being disposed in a plane above that of said shafts.

JOHN C. STUTZ.
